UNITED STATES PATENT OFFICE

141,331

DESIGN FOR A PICTURE FRAME

James Tavianini, Los Angeles, Calif.

Application January 13, 1945, Serial No. 117,416

Term of patent 7 years

(Cl. D29—20)

To all whom it may concern:

Be it known that I, James Tavianini, a citizen of the United States, residing at Los Angeles, in the county of Los Angeles, State of California, have invented a new, original, and ornamental Design for Picture Frame, of which the following is a specification, reference being had to the accompanying drawings forming part thereof:

Fig. 1 is a perspective view of the picture frame embodying my new design;

Fig. 2 is a view in front elevation of the same;

Fig. 3 is a top plan view of the same;

Fig. 4 is a bottom plan view of the same;

Fig. 5 is a view in end elevation of the same; and

Fig. 6 is a sectional view on an enlarged scale taken substantially upon the line 6—6 upon Fig. 4.

I claim:

The ornamental design for a picture frame, as shown.

JAMES TAVIANINI.
